(57) CLAIM

The ornamental design for a hair curler, as shown and described.

DESCRIPTION

FIG. 1 is a front perspective view of a hair curler, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof;

FIG. 11 is an enlarged detail view of area 11 in FIG. 1 thereof; and,

FIG. 12 is an enlarged detail view of area 12 in FIG. 2.

The evenly-spaced broken lines illustrate portions of the hair curler and form no part of the claimed design. The dash-dot-dot broken lines illustrate enlarged view indicators and form no part of the claim thereof.
